Inventor
JOHN E. BELL

By his Attorney
John E. Dubbell

UNITED STATES PATENT OFFICE.

JOHN E. BELL, OF BROOKLYN, NEW YORK, ASSIGNOR TO FOSTER WHEELER CORPORATION, OF NEW YORK, N. Y., A CORPORATION OF NEW YORK.

WELDED HEAT-TRANSFER APPARATUS.

Application filed May 9, 1924. Serial No. 711,999.

My present invention relates to the construction of regenerative elements alternately exposed to contact with a relatively hot fluid and a relatively cold fluid, to thereby transfer heat from the hotter fluid to the colder fluid. The invention is characterized by the formation of each element of body portion and ribs of metal, separately produced and welded together.

10 The general objects of the invention are to provide regenerative elements of high thermal efficiency and capacity, and of such form and regularity of form that a plurality of such elements may be closely spaced in a stack with gas flow passages through the stack so shaped and distributed as to provide a desirably high gas velocity and good contact of the gas with the elements while at the same time avoiding excessive 20 draft loss in the regenerator.

In a preferred construction each regenerative element is formed by welding to the opposite sides of a bar of wrought steel, transversely extending ribs or projections which may well be in the form of suitably shaped sheet steel punchings. The regenerative elements thus formed may be produced at a relatively low cost, and with the body portion and ribs welded thereto, of the 30 proper dimensions and shape for any intended condition of use.

The various features of novelty which characterize my invention are pointed out with particularity in the claims annexed to 35 and forming a part of this specification. For a better understanding of the invention, however, and the advantages possessed by it, reference should be had to the accompanying drawings and descriptive matter in 40 which I have illustrated and described a preferred embodiment of the invention.

Of the drawings:

Fig. 1 is an elevation in section of a portion of a regenerator in which the present 45 invention is employed;

Fig. 2 is an enlarged section, taken similarly to Fig. 1, through one of the regenerative elements;

Fig. 2^A is a perspective view of one of the 50 projections welded to the regenerative element body;

Fig. 2^B is a perspective view of another projection welded to the regenerative body;

Fig. 3 is a side elevation of the regenerative element; and

Fig. 4 is a plan view of the element.

In Figs. 1 to 3 of the drawings, I have illustrated the use of my invention in connection with a regenerative air heater A of the type disclosed and claimed in my co-pending application Serial No. 689,443, filed January 30, 1924. The air heater shown in these figures comprises a chamber A through which the relatively hot flue gases and the relatively cold air to be preheated alternately flow. In the chamber A are stacked a mass of similar regenerative elements, each of which comprises a strip-like body B, which ordinarily is a bar of rolled steel, and on each side of which are welded a plurality of spaced-apart projections or ribs D each generally similar in form to the half of an elliptical punching of sheet steel divided along the line of its major axis. The planes of the projections D are transverse to the length of the bar B. At intervals along the length of each element rectangular projections C which may be sheet metal punchings, are welded to the opposite sides of the bar B. These projections C form spacing shoulders for the regenerative elements, and in the assembled stack of elements each set of projections C and the portions of the bars B between them form a sort of a baffle wall extending parallel to the plane of Fig. 1, in which the projections C of the elements in each upper row support the elements in the rows above it. Preferably the elements in adjacent horizontal rows are staggered and to permit of the desired close spacing of the superimposed rows of elements, the vertical length of the projections C is made slightly shorter than the vertical depth of the bars B, and each bar B is notched at B' between each pair of projections C to receive the adjacent projections C of elements in the rows immediately above and below.

With regenerative elements formed as described, it is possible to proportion the dimensions of the bars and ribs C and D exactly as required to obtain the maximum capacity and efficiency of a regenerator of given weight and volume for use under a given set of operating conditions. The element bars and ribs may also be shaped to insure the minimum practical draft loss

with flow in either direction. The parts of, said ribs being generally similar in form 20 to the halves of an elliptical plate divided along its major axis.

5. A regenerative element comprising a bar of wrought metal, a series of heat absorbing and dispensing ribs welded to the sides thereof and rectangular lugs welded to the sides of said bar at intervals along its length and adapted to unite with the similar lugs of similar elements assembled in a stack to space the elements apart and to 30 form a means through which the upper elements are supported from the lower elements.

10. While in accordance with the provisions of the statutes, I have illustrated and described the best embodiment of my invention now known to me, it will be apparent to those skilled in the art that changes may be made in the form of the apparatus disclosed without departing from the spirit of my invention as set forth in the appended claims.

15. Having now described my invention, what I claim as new and desire to secure by Letters Patent, is:

1. A regenerative element comprising a bar of metal having a series of parallel spaced-apart ribs welded to each side there-

25. 2. A regenerative element comprising a bar of wrought metal, a series of heat absorbing and dispensing ribs welded to the sides thereof and rectangular lugs welded to the sides of said bar at intervals along its length and adapted to unite with the similar lugs of similar elements assembled in a stack to space the elements apart and to 30 form a means through which the upper elements are supported from the lower elements.

Signed at New York city in the county of New York and State of New York this 35

7th day of May, A. D. 1924.

JOHN E. BELL.
